UNITED STATES PATENT OFFICE.

LOUIS LUNSFORD KENDALL, OF WILLIAMSBURG, KENTUCKY.

PORTABLE DEVICE FOR THAWING FROZEN GROUND.

SPECIFICATION forming part of Letters Patent No. 624,945, dated May 16, 1899.

Application filed April 27, 1898. Serial No. 678,937. (No model.)

To all whom it may concern:

Be it known that I, LOUIS LUNSFORD KENDALL, a citizen of the United States, residing at Williamsburg, in the county of Whitley and State of Kentucky, have invented certain new and useful Improvements in Portable Devices for Thawing Frozen Ground; and I do declare the following to be a full, clear, and exact description of the invention, such as will enable others skilled in the art to which it appertains to make and use the same.

My invention relates to an improved portable heater for thawing frozen ground, and, aside from its general utility for this purpose, it is especially designed to facilitate mining operations during the winter season; and the object is to provide a simple, practical, and effective device of this character whereby the gold-bearing frozen earth may be thawed or the frost extracted, so that the usual mining operations may be pursued without regard to the season.

To these ends the invention consists in the construction, combination, and arrangement of the several parts of the heater, as will be hereinafter fully described, and particularly pointed out in the claim.

The same reference characters indicate the same parts of the device in the different views. The accompanying drawings show my invention in the best form now known to me; but many changes in the details might be made within the skill of a good mechanic without departing from the spirit of this invention as set forth in the claim at the end of this specification.

Figure 1 is a schematic view of my improved heater or frost-extractor. Fig. 2 is a similar view showing a simpler form of connecting the heater with the supply-tank. Fig. 3 is a detail view of one of the burners.

1 denotes the tank or reservoir, preferably provided with a pressure-gage 2 and with an outlet-pipe 3, provided with a valve 4, from which a pipe 5 extends to a universal ball-joint coupling 6. An auxiliary outlet-pipe 7 extends from the bottom of the tank to the main outlet-pipe 5, and it is provided with a stop-valve 8, by means of which communication may be established between the pipes 7 and 5 when desired.

9 denotes that portion of the outlet-pipe 3 which projects within the tank or reservoir, and its free end is provided with a strainer-

hood 10 to prevent any particles of foreign matter which may find their way into the tank passing through the outlet-pipe. I prefer to provide the hood 10 with a pin or stud 12, which engages a central orifice in the guard-collar 13, fixed to the bottom of the tank, so as to protect the pipe 9 against accidental displacement or injury due to the rough handling incidental to mining operations.

14 represents a hand-pump fixed to the tank 1 and communicating therewith by the pipe 15, by means of which the tank may be charged with air, whereby the gasoline may be forced to the point of consumption. The inlet-pipe 16 of the air-pump is provided with a check-valve 17, and a rubber pipe (not shown) may be utilized to refill the tank while in operation and without the necessity of releasing the air-pressure. However, I provide an independent screw-plug 18 for refilling the tank when desired.

From the coupling 6 a pipe 19 extends to the burner-battery 20, and it is provided with an indefinite number of universal couplings 21, by means of which the burner-battery may be adjusted to the work in hand.

I have provided the burner-battery 20 with suitable handles 22 for conveniently manipulating it, whereby the flame may be applied to the surface of the ground or the side of a hill, as in placer-mining.

Instead of the pipe 19, provided with the universal couplings 21, I may use a flexible rubber pipe, in which instance the valve 4 is cut off and the supply taken from the tank by means of the pipe 7 and valve 8.

Having thus fully described my invention, what I claim as new and useful, and desire to secure by Letters Patent of the United States, is—

In combination, the supply - tank, and burner-battery flexibly connected therewith, the aligned handles 22 fixed to said battery, and a controlling-valve fixed intermediate one of said handles and the burner, substantially as shown and described.

In testimony whereof I have hereunto set my hand in presence of two subscribing witnesses.

LOUIS LUNSFORD KENDALL.

Witnesses:

JOHN L. WHITEHEAD,
JOHN W. SILER.
